CLAIM

The ornamental design for a clamp for external fixation orthopedic systems, as shown and described.

DESCRIPTION

FIG. 1 is a top plan view of a clamp for external fixation orthopedic systems showing my new design;

FIG. 2 is an end elevational view thereof;

FIG. 3 is a side elevational view thereof, the opposite side elevational view being a mirror image thereto;

FIG. 4 is an end elevational view thereof, opposite that shown in FIG. 2;

FIG. 5 is a bottom plan view thereof;

FIG. 6 is an enlarged cross-sectional view thereof, taken along the line VI—VI of FIG. 1; and,

FIG. 7 is an enlarged cross-sectional view thereof, taken along the line VII—VII of FIG. 4.

FIG. 1**FIG. 2****FIG. 3****FIG. 4****FIG. 5****FIG. 6****FIG. 7**
